UNITED STATES PATENT OFFICE.

WINFRED MATTHEWMAN, OF INGLETON, ENGLAND.

EYE FOR DOLLS OR TOYS.

1,281,186.

Specification of Letters Patent.

Patented Oct. 8, 1918.

Application filed January 26, 1915. Serial No. 4,435.

To all whom it may concern:

Be it known that I, WINFRED MATTHEWMAN, a subject of the King of England, residing at Morrgarth Cottage, Ingleton, in 5 the county of York, England, have invented new and useful Improvements in Eyes for Dolls or Toys, of which the following is a specification.

This invention relates to improvements in 10 eyes for dolls or which are capable of being applied to toys, rings, pins, advertisement purposes or the like. My object is to arrange and construct an eye having a moving lid or lids arranged in such a manner 15 that on the movement of the doll or object carrying the eye or person carrying the same depends the effect produced. The effect is what I term a winking one, after the manner described in my specification of British 20 Letters Patent No. 19,905/13 and in addition the eye itself is so mounted as to move under the influence of motion from side to side. This movement will be a gradual one and to obtain the effect it is not necessary 25 to move the article carrying the eyes over suddenly in one direction or the other as has been the case with glancing eyes heretofore proposed.

In describing my invention in detail reference is made to the accompanying sheet of 30 drawings similar letters indicating similar parts in which—

Figure 1 represents a part sectional elevation of an eye adapted to move from side 35 to side, said eye having moving lids.

Fig. 2 represents a sectional plan of the device shown in Fig. 1 the upper lid being removed.

Fig. 3 is a view showing in rear elevation 40 the device shown in Figs. 1 and 2.

To carry my invention into effect referring to Figs. 1 and 2 I provide an eye ball E of any suitable material and the eye ball is carried on a pivoted arm E' pivoted to 45 the pin or framework P carrying the lids and all may be inclosed in a suitable frame, such as a doll's head, pin frame, or other suitable carrying means such as a containing socket. As shown in Fig. 2, the frame 50 P is suitably bent or curved to allow the eye to turn sidewise or moved from side to side, and pivoted at or about the outer ends P' are the lids L and L', and the frame P is suitably attached to or carried from the 55 framework carrying the device, a portion F being shown in Fig. 1. The arm E' be-

fore referred to is provided with a slot or like E² (Fig. 2) in which may work a substantially vertical rod C adapted to swing from the framework F of the device. This 60 rod C carries at its lower extremity a weight W. Each lid L L' is provided with arms or like L² L³ having their lower ends connected by links or the like L⁴ and L⁵ (Fig. 1) to the rod C. 65

The weight W may move toward or from the eye in the slot E² and from side to side moving thereby the arm E' and eye E, and on the amount of movement given to the weight by means of oscillation, vibration, or otherwise, will depend the movement of the lids and eye ball, the latter only moving from side to side and not rolling as has heretofore been proposed. Owing to the lower lid L' being coupled to the rod C 70 nearer its pivot at the top than the upper lid which is connected by link L⁴ toward the weight W, the movement of the upper lid consequent on the movement of the weight and rod C will be greater or faster than the lower one and a natural effect is produced. This device may be used singly or in duplicate as desired. 75

I may use eyeballs of any suitable material or pattern and provide eye lashes or representations thereof as desired. In some cases I may employ glass or transparent eyes and provide light in connection therewith and thereby give effect to the device at 80 night. The device may be used on vehicles or be connected with other devices for advertisement purposes, or as toys, pins, mascots, or the like. 85

In some instances instead of employing a metal moving eyelid I may employ merely a frame to which will be attached flexible material, such material being fixed on the inside of the doll's head or like and to the eyelid frame and be extended or withdrawn or contracted as the lids are operated under 90 the influence of movement. 95

What I claim is:—

1. An eye for dolls, toys or the like, comprising a supporting frame, an eyeball pivotally mounted in the frame, movable eyelids associated with the eyeball, a gravity-actuated weight movably mounted in the frame, and means for transmitting movement from the weight to both the eyeball and the eyelids. 105

2. An eye for dolls, toys or the like, comprising a supporting frame, an eyeball piv- 110

totally mounted in the frame, movable eyelids associated with the eyeball, a gravity-actuated weight movably mounted on the frame, and means for causing the eyeball to turn when the weight moves sidewise and for moving the eyelids when the weight moves forward and rearward.

3. An eye for dolls, toys or the like, comprising a supporting frame, an eyeball pivotally mounted in the frame for sidewise movement, movable eyelids associated with the eyeball, an arm projecting rearward from the eyeball and having a longitudinal

slot, a swinging rod suspended from the frame by a universal joint and working in the said arm slot, a weight carried by the rod and means for connecting the said rod with the eyelids to impart movement to the latter, when the rod oscillates forward and rearward.

15

20

In witness whereof I have hereunto set my hand in the presence of two witnesses.

WINFRED MATTHEWMAN.
